Attorney

UNITED STATES PATENT OFFICE

HARRY J. MYERS, OF CENTRAL FALLS, RHODE ISLAND

LOOM TEMPLE

Application filed February 9, 1929. Serial No. 338,844.

This invention relates to certain new and useful improvements in loom temples and pertains more particularly to an improvement upon Patent No. 1,121,194, of Dec. 15, 5 1914.

In said patent the arm which carries the selvage loop retainer is attached to the loom temple by means of a coil spring which in applying same necessitates removal of the 10 temple from the loom, followed by the boring of a hole to receive the anchoring pin for the coil spring. This requires stopping of the loom and necessitates readjustment of the temple in the loom.

The present invention aims to provide an improved manner of connecting the structure supra to the loom, and also one which eliminates the necessity of removing the temple or in any manner affecting its 20 adjustment.

The present invention further aims to provide a simplified form of carrier for the loop retainer and its tensioning means and further to embody such elements in a unitary 25 structure which latter more specifically is secured to the usual temple box by means of the bolt carried by the temple box and projecting upwardly therefrom.

In the drawings:

Figure 1 is a perspective view of the invention, showing same applied to the temple box, and

Figure 2 is a top plan view of the invention showing same in position in the loom.

In proceeding in accordance with the present invention, a bracket 1 of substantially L-shape is employed and which engages over the forward end of the usual temple box 2 of the loom, this temple box carrying the 30 customary pinrolls and has the usual bolt 3 projecting vertically therefrom. The bolt is removed, and the bracket applied whereupon the bolt is then passed through a slot 4 in the upper side of the bracket 1, and the bolt 40 tightened thereby to clamp the bracket to the temple box. The vertical arm of the bracket has a stop pin 5 projecting outwardly therefrom and further carries a set screw 6, to which is pivoted a loop or eye 7 formed in 45 the side 8 of a spring arm 9, the arm 9 being

of substantially U-shape and preferably has a coil 10 formed intermediate its ends. The arm is formed preferably of spring wire, and has its side 8 extended outwardly at 9' to engage the stop pin 5 and thence is extended 55 along the side of the temple box as shown at 10 and carries the usual selvage loop retainer 11 on the free end of the part 10. A strap 12 which may be of leather, is pivoted at one end to the stop pin 5, while its opposite end is 60 provided with a series of openings 13 to receive the right angular end 14 of the other side 15 of the spring arm. By forming the strap 12 of leather or other flexible material 65 it will be seen that the strap can be easily secured in position and can be flexed so as to enable the right angular end 14 of the side 15 to be placed in any one of its apertures 13, thereby to tension the arm in accordance with the various degrees of tensioning, such as 70 may be required or found desirable.

From the foregoing it will be seen that the entire structure is carried by the bracket 1, the latter affording a unitary mounting for the stop pin and for the screw, which latter 75 supports the arm, while the stop pin provides a pivotal mounting for the strap. Thus the entire device can be applied and removed as a unit, without in any way disturbing the temple or its adjustment.

The lay, which swings toward the breast beam, engages the side 8 of arm 9 and thereby swings the latter raising the loop retainer 11 above the line of the cloth. As the lay returns to normal the spring properties of the 85 arm effects return of the retainer 11 to its normal position, as in my said previous patent.

It will be noted that the arm 9 may be manually swung rearwardly above the screw 6 90 as a pivot and when so thrown back same will be held latched, due to the spring action of the parts and will thus be held in a position so as to not interfere with free handling of the yarn.

Having thus described my invention what I claim as new and desire to secure by Letters Patent is:—

1. A device of the type set forth for attachment to the box of a loom temple, which 95

temple box has a bolt, comprising a bracket of angular form engaged over an end of the box and having an aperture to receive the bolt and to be clamped thereby to the box, a substantially U-shaped spring arm having one of its sides extended outwardly and then rearwardly and carrying a selvage loop retainer, a screw to pivotally connect said side of arm to the bracket, a stop pin carried by the bracket and engageable with the outwardly extended part of said side of the arm, and a strap pivoted to said pin and extending across the space between the sides of the arm and having a series of spaced apertures to receive the other side of the arm in a selected one thereof, said other side of the arm having an angular free end for supporting the strap.

2. A device of the type set forth for attachment to the box of a loom temple, which temple box has a bolt, comprising a bracket having means to receive a bolt so as to be held in position thereby, a substantially U-shaped spring arm having one of its sides extended and carrying a selvage loop retainer, means to pivotally connect said side of the arm to the bracket, a stop on the bracket engageable with said extension, and a strap pivoted to the bracket and engaged with the other side of the arm.

3. A device of the type set forth for attachment to the box of a loom temple, which temple box has a bolt, comprising a bracket having means to receive the bolt so as to be held in position thereby, a substantially U-shaped spring arm having an extension on one of its sides provided with a selvage loop retainer, means to pivotally connect said side of the arm to the bracket, a stop on the bracket engageable with said extension, and means connected to the other side of the arm and pivoted to the bracket for causing the spring arm to have its extension yieldably held in engagement with the stop.

4. A loom temple attachment including a substantially U-shaped spring arm having a selvage loop retainer on the inner side thereof, means to pivotally connect the arm to the temple box, stop means engageable with the arm to limit pivotal movement thereof in one direction, and a strap pivoted to the temple box and connected to the outer side of the arm above said pivotal point of the strap to yieldably hold the arm engaged with the stop means.

5. In a loom temple, a substantially U-shaped spring wire member having the inner side thereof extended and formed with an eye and with a selvage loop retainer, means extending through the eye to pivotally connect the member to the temple box, a stop for limiting the pivotal movement of the member in one direction, and a strap pivotally connected to the box and to the outer side of the member at a point above said pivotal

point of the strap for holding the member against the stop.

6. In a loom temple, an arm having a selvage loop retainer, means to pivot the arm to the temple box, a stop engageable with the arm to limit pivotal movement thereof in one direction, means connected to the arm to hold the arm engaged with the stop, and means to pivotally connect the holding means to the temple box whereby to hold the arm against the stop and to enable the arm to be manually swung rearwardly out of operative position and be held latched in inoperative position by the holding means.

7. In a loom temple, an arm having a selvage loop retainer, means to pivot the arm to the temple box, a stop engageable with the arm to limit pivotal movement thereof in one direction, means connected to the arm to hold the arm engaged with the stop and means to connect the holding means to the temple box whereby to hold the arm against the stop and to enable the arm to be manually swung rearwardly out of operative position and be held latched in inoperative position by the holding means.

In testimony whereof I have signed my name to this specification.

HARRY J. MYERS.
